UNITED STATES PATENT OFFICE.

ARNOLD MOETTELLI, OF OBERWINTERTHUR, SWITZERLAND.

COKE-COOLING APPARATUS.

Application filed December 28, 1921. Serial No. 525,518.

To all whom it may concern:

Be it known that I, ARNOLD MOETTELLI, a citizen of Switzerland, residing at Oberwinterthur, Switzerland, have invented certain new and useful Improvements in Coke-Cooling Apparatus, of which the following is a specification.

It is already known to utilize the high temperatures of hot coke leaving the retorts, for the generation of water gas, by quenching the coke by introducing steam in an air-tightly closed chamber and passing the water gas formed to further utilization. The steam required for this purpose is usually tapped from an existing steam boiler plant.

This process has the drawback, that only the heat of an upper zone of temperature of the incandescent coke can be employed economically, since with a temperature of the coke below 600 degrees centigrade a generation of water gas will no longer take place, and even below 700 degrees centigrade it will become uneconomical to such an extent, that it can not be carried through practically. The heat of the lower zone of temperature, that is to say below 700° C. is thus lost. Besides it is necessary to generate the steam required for the generation of water gas by a corresponding consumption of fuel, which procedure will minimize the profit obtained by the formation of water gas.

In the new process according to the invention both the water gas and the steam required for that purpose are obtained by means of the heat contained in the incandescent coke. The process consists in utilizing the heat yielded at an upper zone of temperature from a quantity of coke contained in a receptacle for making water gas, while the heat gained at a lower zone of temperature from the same charge of coke is used for the generation of the steam required for the formation of water gas, the whole procedure with the object in view to dispense with a special source of heat for the generation of steam.

The installation for carrying out this process may be of such construction that the stoking hole or fire place of the boiler serving for the generation of steam, is connected with the receptacle containing the coke by means of pipes capable of being shut, and through which, after opening of the shutting-off members, the gases contained in both the communicating chambers, for the pur-

pose of conveying the heat of the coke into the boiler, are forced by means of a blower in a cycle through the receptacle and the boiler. The plant may also be of such construction, that conduit pipes are provided through which the water gas generated may be conducted either directly or through the stoking hole of the boiler to the place of consumption.

A mode of construction is shown in the drawing.

a is a receptacle into which the coke coming from the retorts is introduced through the opening *b* and after the finishing of the cooling process is discharged through the outlet *c*. *d* represents a boiler, whose stoking hole is connected at the top with the receptacle *a* by means of the pipe *e* and at the bottom by the pipe *f*. A blower *v* is arranged in the duct *f* forcing the gases contained in the receptacle for the coke and the stoking hole in a cycle through both chambers, in order to transfer the heat, withdrawn from the coke by the gas, to the boiler. *g* and *h* are shutting-off members provided for the purpose of temporarily interrupting the communication between the coke chamber and the stoking hole.

Connected with the steam chamber of the boiler is a steam pipe *i* leading to the coke chamber, by means of which the steam required for the generation of water gas is conducted to the coke. For regulating the admission of steam said pipe is provided with a controlling member *k*. The water gas generated is passed through the pipe *l* provided with a closing member *m* to an accumulator or as the case may be to the place of consumption.

Another pipe *n* having a closing member *o* serves for conducting the hot water gas through the stoking hole or fire place of the boiler with the object of utilizing the heat of the gas.

The plant is operated in such a manner, that the total amount of heat yielded by the first filling of the container *a* is used for the generation of steam. For this purpose the closing members *k*, *m* and *o* are shut, and *e* and *f* opened, and the blower *v* started, whereby the gases forced through the communicating chambers in cycle, transfer the heat of the coke to the boiler water, and cause vaporization of the latter.

If sufficient steam is generated in this way, the container *a* is discharged and filled

again with incandescent coke, the closing members *g* and *h* are shut, *m* opened and thereafter steam is passed into the incandescent coke by opening the controlling member *k*. The water gas generated hereby is conducted through the conduit pipe to the accumulator or place of consumption respectively. As soon as the coke cooling down has reached a temperature of about 10-700°, the members *m* and *k* are closed, but *g* and *h* opened, and by starting the blower *v* the heat still inherent in the coke is again utilized for the generation of steam. In this manner it is possible to generate the steam required for the formation of water gas following next.

After the complete cooling of the coke the container is discharged and a new charge of incandescent coke brought in, when after 20 a corresponding adjustment of the closing members the formation of water gas and the

subsequent generation of steam commences anew. Instead of leading the hot water gas, leaving the coke container, to the accumulator directly or to the place of consumption, said gas can also be conducted through the boiler by closing the member *m* and opening the member *o*, where its heat is utilized in an economical way for the further generation of steam. 25 30

I claim:

A plant for dry cooling coke comprising in combination a cooling chamber, a steam boiler connected therewith, a valved means for introducing steam from the boiler into 35 the chamber, a valved means for drawing off water-gas and valved means for circulating a cooling gas through the chamber and then through the boiler.

In testimony whereof I have affixed my 40 signature.

ARNOLD MOETTELL.
